 corporation of Maryland

Application June 19, 1942, Serial No. 447,636

19 Claims. (Cl. 309—14)

1

This invention relates to a piston and is more particularly directed to a piston for use in internal combustion engines.

It is quite common in the art to manufacture pistons of iron or steel castings for internal combustion engines although such pistons have undesirable qualities in so far as the transmission of the heat of combustion away from the combustion chamber is concerned. Such pistons must be provided, as a general rule, with a relatively thick head wall in order to withstand the heat of combustion developing within the combustion chamber without producing hot spots, burn outs and the like. Too thin a wall in the head region will result in hot spots appearing which will eventually lead to burn outs. By increasing the wall thickness at this region, the danger of burn outs is prevented but the heat transmitting qualities of the head are reduced.

Pistons have also been manufactured of aluminum castings, which material is a much better conductor of heat than cast steel or cast iron. Aluminum, however, has a much higher coefficient of expansion than cast iron, of which the cylinder walls are generally constructed, and it is necessary to fit such pistons to the cylinder wall while the pistons are warmed to a temperature approaching that at which they will operate. Such hot fitting results in the piston's being considerably undersized at temperatures below the fitting temperature. This has the effect of causing the piston to slap and be extremely noisy when the engine is first started and until the piston has warmed up to proper operating temperature. Additionally, aluminum is considerably more expensive than is cast iron or steel.

The steel or cast iron pistons, however, have approximately the same rate of expansion as the cylinder wall with which they are used and can be fitted rather closely at relatively low temperatures with the assurance that these fits will be maintained at operating temperature. The principal difficulty with cast iron or steel is that, due to the previously mentioned head thickness, the heat is not conducted away from the combustion chamber as rapidly as is the case with aluminum and it is therefore not possible, as a general rule, to employ compression ratios in connection with cast iron or steel as high as those employed with aluminum; consequently, knocking or detonation caused by self-ignition of the combustibles in the combustion chamber is much more prevalent in connection with iron or cast steel than is the case with aluminum.

The piston of the present invention has been

2

designed with a view to taking advantage of the similarity of coefficients of expansion of the cylinder wall and a steel piston and yet to make provision for rapid conduction of heat away from the head of the piston by providing means for cooling the piston head, which, in this instance, is an extremely thin walled structure reinforced with a box-like section for the purpose of increasing its strength.

10 It is an object of this invention to provide an extremely thin walled piston made up of steel stampings and properly reinforced at its load-bearing points by further light stampings in such a way as to increase the strength without impairing the desirable qualities flowing from thin walled sections.

15 It is a further object of this invention to provide means in a piston whereby a cooling fluid may be circulated over the highly heated portions 20 of the piston so as to extract heat therefrom rapidly and efficiently.

25 It is a further object of this invention to permit an increase of the compression ratios heretofore permissible with steel pistons by using a means for efficiently cooling the pistons.

Other objects and advantages inherent in the 30 invention will be recognized as this description proceeds and will be more particularly pointed out in connection with the claims appended hereto.

35 In the drawings, of which there are three sheets:

Figure 1 is a vertical, transverse, sectional view through a portion of an internal combustion engine showing the piston of the present invention in section and in position within the cylinder and showing its attachment to the crankshaft through the connecting rod;

Figure 2 is a horizontal sectional view of the 40 piston shown in Figure 1 taken along the line 2—2 and looking in the direction of the arrows;

Figure 3 is a vertical, longitudinal, sectional view of the piston taken upon a plane as indicated by the line 3—3 of Figure 2;

45 Figure 4 is a detailed sectional view through a portion of the piston head and illustrating a step in the method of assembly of the same;

Figure 5 is a vertical, longitudinal, sectional view of a modified form of the piston constituting 50 the present invention;

Figure 6 is a horizontal sectional view through the piston shown in Figure 5 taken upon a plane as indicated by the line 6—6 of Figure 5 and looking in the direction of the arrows;

55 Figure 7 is a vertical sectional view similar to

Figure 5 showing a still further modification of the invention;

Figure 6 is a horizontal sectional view of the piston taken upon a plane as indicated by the line 8—8 of Figure 7 and looking in the direction of the arrows;

Figure 9 is a vertical, longitudinal, sectional view through a piston representing a still further modification of the invention;

Figure 10 is a horizontal sectional view taken upon a plane as indicated by the line 10—10 of Figure 9 and looking in the direction of the arrows;

Figure 11 is a plan view of a still further modified form of the piston;

Figure 12 is an elevational view of the piston shown in Figure 11;

Figure 13 is a horizontal sectional view through a piston taken upon a plane as indicated by the line 13—13 of Figure 12;

Figure 14 is a vertical, longitudinal, sectional view taken upon a plane as indicated by the line 14—14 of Figure 12;

Figure 15 is a sectional view taken upon a plane as indicated by the line 15—15 of Figure 11; and

Figure 16 is a plan view of the inner shell shown in Figures 13, 14 and 15.

Referring in more detail to the drawings, in which similar reference characters are employed throughout to designate similar parts, the invention will be recognized as residing in a piston 20 which is connected through a piston pin 22 to a connecting rod 24 which is supported upon a crank pin 26 from a crankshaft 28 of an internal combustion engine. Crankshaft 28 is supported in bearings (not shown) which may be supplied in the usual manner with lubricating oil from a pressure lubricating system. The crankshaft is drilled throughout its length as at 30 to receive oil from its bearings and conduct the same through drilled passageways 32 in the cheek plates 34 to conduct oil to the crank pins 26. Crank pins 26 are each drilled radially as at 36 to supply oil to the bearing surface 38 between the connecting rod 24 and crank pin 26.

The bearing bushing 40 forming the bearing surface 38 is provided with a slot 42 adapted to be aligned once during each rotation of the crank pin 26 with the oil outlet 36. The bearing insert 38 may be maintained against rotation within the crank pin end of the connecting rod by any suitable means and is aligned in its thus fixed position with two apertures constituting entrances to oil passageways 44 and 46. The oil passageway 44 terminates upon the upper side of the crank pin end of the connecting rod in a metered nozzle 48 which is adapted once during each rotation of the crank pin to emit a stream of oil therefrom. This stream of oil will be emitted as the piston approaches its top dead center position to cause a deposit of lubricating oil upon the walls of the cylinder indicated at 50. The oil passageway 46 extends upwardly centrally of the connecting rod 24 for the purpose of supplying oil within the wrist pin eye 52 of the connecting rod 24.

The wrist pin eye 52 is bushed as at 54 and such bushing is provided with a groove 56 extending completely therearound. The upper end of the connecting rod terminates in a drilled nozzle 58 which is adapted to emit a stream of oil against the underside of the head of the piston 20 once during each revolution of the crankshaft.

The piston shown in Figure 1 is made up of stampings and comprises an outer cylindrical

shell 60 having an upper reduced cylindrical portion 62 of smaller diameter than the skirt portion 60 and concentrically arranged with respect thereto. The upper or head end of the outer stamping is provided with an integral wall 64 forming a closure for the upper end of the piston, such wall being provided with a downwardly drawn centering depression 66 for the purpose of receiving a tool, as will be shortly explained. The lower end of the skirt 60 of the outer shell is provided with an inwardly and upwardly flanged portion 68 which may be conically shaped upon its inside for receiving a centering tool.

15 The portions 68 and 66 are provided for the purpose of permitting the reception of the piston, after it has been completed, within a grinding machine, the piston being centered upon the surfaces 66 and 68. It will be understood, of course, that these are not employed until the entire piston has been assembled and welded to its final shape.

Nested within the outer shell 60 is an inner reinforcing member 70. Inner shell 70 may take the form of a shallow cylinder having oppositely disposed ribs 72 upon its front and rear surfaces and extending vertically with respect to the piston. Depending from the underside of the shallow cylinder forming the principal part of the inner shell 70 are ears 74 which may be located at the front and rear of the piston and form, in a sense, extensions of the ribs 72.

Returning for the moment to the outer shell 60 and referring specifically to Figure 3, it will be noted that the outer shell is provided with depressions 76 at opposite sides thereof and located upon a diameter of the outer cylindrical shell, such depressions 76 terminating in inwardly extruded and flanged portions 78 defining cylinders within which may be received a piston pin bushing 80. Piston pin bushing 80 is arranged to receive the wrist pin 22 when the connecting rod and piston are assembled. Ears 74 are provided with conical depressions 82 similar to the conical depressions 76 in the outer shell and these conical portions 82 are also extruded and inwardly flanged as at 84 to provide an additional set of cylindrical orifices aligned with the inwardly flanged portions 78 of the outer shell. 35 The wrist pin bushing spans both cylindrical flanged elements 78 and 84 on one side of the piston, two such bushings being employed, and serves rigidly to connect the inner and outer shell adjacent the sides of the piston. The piston pin 40 22 is located lengthwise within the bushings 80 by means of snap rings 23.

The upper end of the inner shell is closed by an end wall 86, such end wall being provided with an elliptical opening 88 surrounded by an upwardly extending flange 90. The opening 88 is arranged with its long axis extending transversely of the piston or in the same plane as the plane of rotation of the crank pin 26 so as to permit a relatively long sweep of the oil nozzle 58 during the period that the opening 88 receives oil therefrom. It will also be noted that the opening 88 is centered upon the depression 66 so that the depression 66 serves to distribute radially with respect to the piston head the oil received 55 through the opening 88.

The end closure 86 of the inner shell is spaced from the end closure 64 of the outer shell by means of a sinuously corrugated steel ribbon 92. This ribbon is relatively thin with respect to its width and the corrugations are employed for the

purpose of stabilizing it so that it may be stood on its edge as shown in Figures 1 through 4. The corrugated ribbon 92 is fashioned into a rosette form as shown in Figure 2. Ribbon 92 may be provided along its lower edge with a series of notches 94 which extend through only about a quarter of the width of the ribbon. Notches 94 permit oil which is trapped within the rosette to flow to the outside of the rosette in order that the oil may act as a cooling fluid both on the inside and outside of the corrugations formed by the ribbon and against the underside of the entire surface of the piston head 64.

Oil which has been sprayed from the nozzle 58, has struck the downward projection formed by the depression 66 and been deflected over the top edge of the flange 90 of aperture 88 will rest upon the upwardly presented surface of the end closure 86 with the flange 90 acting as a dam to prevent return flow through aperture 88 and will flow along the top surface of closure 86 and through the notches 94 to the outside of the rosette and will be returned to the oil reservoir in the lower half of the crankcase by means of apertures 86 arranged around the outer periphery of the inner shell closure 86.

A portion of the oil so circulated will be returned along the inner wall of the outer shell by means of the grooves 88 formed by the ribs 72. Oil flowing through the grooves 88 and down the inside of the outer shell 60 will be trapped at the lower edge of the piston by the upwardly flanged portion 68 and will be returned to the reservoir through apertures 100 arranged at the bottom of the trough 102 formed by the flange 68. Apertures 100 will direct the oil accumulated in the trough 102 against the cylinder wall 50 and will serve as means for lubricating the cylinder wall 50 in addition to nozzle 48.

Attention is directed to Figure 4 which shows the method of assembly of the outer shell 60, inner shell 70 and the rosette formed by the ribbon 92. The parts are shown in Figure 4 as loosely assembled just prior to the operation in which they are pressed into contact with one another. It will be understood that the outer surface of the cylindrical portion 70 of the inner shell has a pressed fit with the inner surface of the reduced cylindrical portion 62 of the outer shell as shown in Figure 4. The outer shell 60 is inverted, the rosette dropped in place upon the inside surface of the head closure 64 with the notches 92 upwardly disposed in this position and then the inner shell 70 is placed within the reduced cylindrical portion 62 of the outer shell and forced down into position. It will be noted that the head or end wall 64 of the outer shell 60 is shown slightly dished in Figure 4 while the end closure 86 of the inner shell is shown as being slightly deformed upwardly. The rosette formed by the ribbon 92 is, however, of uniform vertical extent throughout and consequently that portion of the rosette toward the center of the piston will be the first to seat upon both the under surface of the head 64 and upon the upper surface of the closure 86 as the inner shell 70 is pressed upwardly into place.

Attention is directed to the clearance 104 existing between the upper surface of the rosette and the under surface of the head 64 as well as to the clearance 106 which exists between the bottom surface of the rosette and the upper surface of the inner shell head closure 86. As the assembly operation continues, the upwardly deformed end closure 86 will be returned to a single plane

and the dishing which is apparent in Figure 4 in the head 64 will be flattened out so that each of these parts is returned to a single plane and each part is seated throughout its extent upon adjacent portions of the rosette. This serial seating of the rosette edge portions upon both the inner and outer head forming elements insures solid contact throughout the entire extent of the edge portions of the rosette with both of these elements and makes it possible later to perform a hydrogen welding operation upon the entire piston. Solid contact of the rosette with both parts and the subsequent hydrogen welding provide for efficient heat transfer from head 64 through the rosette and to closure 86.

The reduced cylindrical portion 62 of the outer shell 60 is provided for the purpose of forming a seat for a plurality of flanged rings 108. Flanged rings 108 are pressed downwardly over the outside of the reduced cylindrical portion 62 into abutting relationship with one another and with their flanges outwardly extending and spaced from one another. It will be noted that the rings 108 do not extend completely to the top surface 64 of the outer shell and the gap left between the topmost ring 108 and the head of the outer shell 64 is filled by means of a U-shaped ring 110 which may be made up of two parts of similar section which are reversed and secured to one another as by resistance welding. The inner edge 112 of the U-shaped ring 110 may be secured as by tack welding at 114 to head 64 to hold the rings 108 in place. The grooves which are formed between the flanges of the rings 108 are adapted to receive piston rings 116 such as are usually provided upon the pistons of internal combustion engines.

However, before the piston rings 116 are assembled upon the piston, it is necessary to secure all of the other elements making up the piston to one another in a permanent fashion and this is accomplished by so-called hydrogen welding, which comprises heating the piston in the presence of a copper brazing material and in a hydrogen atmosphere. This operation causes the flow of the copper brazing material to all of the joints and results in a uniting of the parts through these joints by means of the copper. After the brazing operation, the piston is allowed to cool and is chucked upon tools between the conical surfaces 66 and 68 and finish ground to the desired final form, which in most instances is slightly elliptical.

The hereinbefore described method of assembly has been made the subject matter of a co-pending application of Floyd F. Kishline for Method of assembling a piston, Serial No. 551,357, filed August 26, 1944, now Patent No. 2,437,824.

After final grinding, the lowermost ring 108 may be drilled at spaced intervals as shown at 118, the aperture extending through the upper reduced cylindrical portion 62 of the outer shell so as to provide means for returning to the reservoir oil scraped from the cylinder wall by the lowermost or oil piston ring.

Referring to the modification shown in Figures 5 and 6, the same type of outer shell 60 is employed having a reduced cylindrical upper portion 62 and using a rosette made up of corrugated ribbon 92, the principal difference between the piston shown in Figures 1 to 4 and the piston in Figures 5 and 6 residing in the inner shell.

In this instance the inner shell 170 is flattened off adjacent the conical depressions 76 and extruded flanges 78 of the outer shell 60 to form a flat wall 171 which extends downwardly ad-

7 jacent each side of the inner shell 170 and transversely of the piston and is provided with a pierced and extruded portion to form flanges 184 for receiving the piston pin bushing 180. oil which is received through the flanged aperture 188 and distributed laterally by means of the conical projection formed by depression 68 may be returned to the reservoir through the relatively wide spaces 198 existing by reason of the provision of the flat wall 171 upon the inner shell 170. A plurality of ribs 172 may be provided in the inner shell which extend downwardly through only a portion of the cylindrical shell, such ribs terminating in apertures 196 which are employed for returning the remainder of the oil to the oil reservoir. Radially extending ribs 173 may be provided in the head 186 of the inner shell to reinforce the same.

The inner shell 170 also differs from the inner shell of the first modification in that the flanged aperture 188 is circular in outline although still centrally placed in the closure 188 of the inner shell.

Instead of employing a plurality of flanges to form piston ring grooves, this piston utilizes a sleeve 200 of cast iron in which the piston ring grooves 202 may be cut as by turning. The sleeve 200 is held in place against the shoulder of the outer shell by means of a stamped ring 203 which may be secured as by tack welding 204 to the head portion of the outer shell. The space 205 within the ring 203 is vented by means of apertures 206 to the interior of the piston. These apertures 206 function to prevent overheating of the space within the ring 203 such as might be likely to cause the ring to buckle and distort. Oil return apertures 218 may be drilled through the reduced diameter 62 of the outer shell and the sleeve 200 in order to provide an outlet return to the reservoir for oil which is scraped from the piston walls by the action of the oil ring, which constitutes the lowestmost of the piston rings.

Referring to Figures 7 and 8, which constitute a further modification, it will be noted that in this instance the outer shell 260 is formed along lines generally similar to the outer shell 60 of Figures 1 and 6 but the shell is not provided with an integral head closure; instead the upper edge of the reduced portion 262 terminates in a flange 263 providing an upwardly presented flat surface, the inturned edge of the flange being serrated as at 259 to provide seats for locating and aligning the bights forming the periphery of the rosette. After the ring sleeve 202 is placed in position, an end closure 264 is fitted to the ring sleeve 202 and is pressed downwardly against the upwardly presented surface of the annular flange 263. The flanged edge 265 of the end closure 264 terminates upon the ring sleeve at the level of the upper edge of the upper piston ring groove and has a pressed fit with the ring sleeve 202. The inner shell 270 is again provided with flattened portions 271 extending transversely to the axis of the piston pin and these flattened portions are provided intermediate their extremities with a strengthening rib 273, strengthening ribs 272 being provided adjacent the sides of the piston in the inner shell and extending from top to bottom thereof for the purpose of conducting oil therethrough. The corrugated ribbon 92 is again employed for the purpose of spacing the inner shell from the head closure 264 and is received within serrations 259 as previously explained. Venting

apertures 208 are again provided for the purpose of relieving the pressures that may build up due to the heat within the space 205 at the upper periphery of the piston.

5 Referring to Figures 9 and 10, it will be noted that in this modified form of the piston the outer shell 360 has a reduced cylindrical portion 362. The upper extremity of the outer shell terminates in an inwardly flanged ring 363. Ring 363 is made up of a series of radially extending lands 367 which extend from the central aperture 388 to the outer extremity of the reduced diameter 362. An additional series of lands 369 of smaller radial extent are located 10 between the lands 367. The top surfaces of each of lands 367 and 369 lie in a common plane, the remainder of the flanged portion 363 lying therebelow. A head closure member 364 which has a downwardly extending annular flange 364 is adapted to be secured as by hydrogen welding 20 to the surfaces of the lands 367 and 369.

It will be noted that the underside of the flange 363 slopes downwardly and outwardly for the purpose of more efficiently conducting cooling oil therewith in contact with the underside of the head closure 364. It will also be understood that the underside of the downwardly extending depression 366 acts to distribute oil laterally into the channels formed by 25 the lands 367 and 369. Oil thus directed will flow radially outwardly into the space 385 formed by the downwardly extending flange 363 of the head closure 364 and will be returned to the oil reservoir through the apertures 306 in 30 the upper portion of the reduced cylindrical upper part 362 of the outer shell 360. Oil may be returned to the reservoir as it is scraped off the cylinder wall by the oil ring by means of 35 the apertures 318 extending through the cylindrical portion 362 and the piston ring sleeve 302.

40 Against the underside of the flanged portion 363, there is secured as by welding an inner shell 370 formed to fit within the reduced cylindrical portion 362 but also provided with flat transversely extending side wall portions 371. Side wall portions 371 may be grooved as at 373 for strengthening purposes. The upper edges of the flat wall portions 371 of the inner shell 370 are flanged as at 375 for attachment to the underside 45 of the inner shell flanged portion 363. It will be noted that the flanges 375 terminate adjacent the sides of the piston and that the inner shell is cut away as at 391. It will also be noted that the flanges 375 do not extend at right angles 50 to the walls 371 but instead are bent to align with the under surface of the flanged portion 363 which is arranged to drain oil radially outwardly of the piston.

55 Referring to Figures 11 to 16, a still further modification of the invention appears. In this instance the outer shell 460 is formed as a unitary stamping complete with the upper reduced portion 462 and a head closure 464. An inner shell 470 is provided which has a cylindrical portion 472 arranged to have a pressed fit with the inner cylindrical surface of the reduced cylindrical portion 462 of the outer shell. The upper surface of the inner shell 470 comprises a generally flat under surface 471 in which there are 60 provided four lands 473 equally spaced over the surface of the flat portion 471 and extending upwardly for contact with the under surface of the head closure 464. The spaces 475 between the lands 473 form channels for the purpose of 65 conducting cooling oil radially outwardly in con-

tact with the head closure 464 and into an annular space 477 formed by the conical upper side walls 479 of the inner shell 470. Oil within the space 477 is returned to the oil reservoir in the crankcase by means of the grooves 481 formed by the strengthening ribs 483 adjacent the sleeves 480 forming the piston pin supports and also by means of apertures 496 provided in the conical portion 479 of the inner shell 470.

As in the case of the modification shown in Figures 1 to 4, the piston ring grooves in Figures 11 to 16 are formed by a series of flanged rings 408 which are held in place upon the reduced cylindrical portion 462 by a pair of flanged rings 410 secured as at 412 to the outer end closure 464. Provision for venting the volume within the rings 410 may take the form of apertures 412 extending through the wall 462.

It will be understood that in all of the modifications described, the component parts of the piston are similarly secured to one another by a hydrogen brazing process. It has been found that this process functions excellently to preserve the parts in their original relationship under all conditions of heat encountered within the cylinder. This end result is believed to be due, to a large extent, to the use of the cooling oil which is sprayed against the underside of the head and distributed by the channel forming means once during each revolution of the crankshaft. It has been found that in spite of the high temperatures encountered upon the piston head, there is no visible carbonization of the oil and that no "varnishing effect" of the oil is apparent after many hours of testing under very severe conditions. This is believed to be due to the fact that fresh quantities of cool lubricant are constantly being ejected against the piston head and are removing the heat at its point of application rather than requiring the heat to flow downwardly along the piston wall and be transferred across the juncture of the piston and cylinder wall and into the cooling water in the jacket 81 (see Figure 1). This removal of the heat before it is required to travel any appreciable distance improves the wear of both the piston and the cylinder wall as the lubrication conditions of the cylinder wall are considerably improved due to its operation at a much lower temperature than previously.

While the invention has been described in considerable detail, the foregoing description is not to be taken as limiting but simply as illustrating the invention. All equivalents falling within the scope of the appended claims are hereby expressly reserved.

I claim:

1. A piston comprising an outer cylindrical stamping, the side walls of said stamping being extruded inwardly of said stamping to form aligned apertures along a diameter of the piston, an inner stamping nested within said outer stamping and secured to said outer stamping, depending portions on said inner stamping spaced inwardly from said outer stamping and apertured and flanged in alignment with the extruded and flanged portions of said outer stamping, and bearing sleeves positioned in said aligned apertures at each end of said diameter.

2. A piston comprising an outer cylindrical stamping having side walls extruded inwardly of said stamping to provide cylindrically flanged aligned apertures along a diameter of said stamping, an inner stamping nested within said outer stamping and having depending portions spaced

laterally from the side walls of said outer stamping and pierced and extruded along said diameter to provide cylindrically flanged apertures aligned with the flanged apertures in said outer stamping, and a bearing sleeve secured within said aligned apertures and spanning the space therebetween at each end of said diameter.

3. A piston having an outer stamped shell, a smaller inner stamped shell within said outer shell, and means securing said outer and inner shells together comprising means closing the head of said outer shell, means forming an end wall of said inner shell, means spacing said head closing means and said end wall from one another and securing them in spaced relation to form a strengthening element, and means adjacent the end of said inner shell opposite said end wall securing said inner and outer shells in spaced relationship.
- 10 4. An internal combustion engine having an oil distributing system, a crankshaft, a connecting rod carried by said crankshaft, and a piston having a head and carried by said connecting rod, means for supplying oil from said system to the underside of said piston head and retaining it in contact therewith comprising, an oil nozzle in said connecting rod adjacent the underside of said piston head and arranged to discharge thereagainst, a baffle spanning said piston below said head and having a central oil receiving aperture which aligns with said nozzle, and discharge ducts from said baffle located adjacent the periphery of said baffle.
- 15 5. A piston comprising an outer shell, a head for said outer shell, a baffle arranged within and spanning said shell, means spacing said baffle below said head, said baffle providing a centrally arranged aperture, and peripherally arranged apertures located adjacent the periphery of said baffle.
- 20 6. A piston comprising an outer shell, a head closing the end of said outer shell, a baffle arranged within and spanning said outer shell, means spacing said baffle below said head, said baffle providing a centrally arranged aperture, flanges projecting upwardly around the periphery of said aperture, and other apertures located adjacent the periphery of said baffle.
- 25 7. A piston for an internal combustion engine comprising an outer cylindrical shell, means forming a closure for one end of said shell, an inner shell nested within said outer shell and having an inner end wall spaced from said closure means, means connecting said closure means and end wall in spaced relation with respect to one another, and means upon a diameter of said outer shell spacing said inner shell therefrom.
- 30 8. A piston for an internal combustion engine comprising an outer shell having an end closure, an inner shell nested within said outer shell and having an end wall, a spacer member located between said closure and wall and in contact therewith at spaced points, and means securing said spacer member to said outer and inner shells to hold said wall and closure so spaced.
- 35 9. In combination with an internal combustion engine having a pressure lubricating system, a piston comprising a shell having a skirt and a head, a baffle located within said shell and spanning the interior thereof below said head, means spacing said baffle from said head over a portion only of said head to provide channels extending radially of said head, an inlet formed in the central portion of said baffle, outlets from said chan-
- 40 75

11

nels, and means for delivering lubricant from said pressure system to said baffle inlet.

10. A piston having an outer shell, a smaller inner shell within said outer shell, and means securing said outer and inner shells together comprising means closing the head of said outer shell, means forming an end wall of said inner shell, and a rosetted ribbon arranged between and spacing said head closing means and said end wall from one another and secured thereto to form a structural head strengthening element.

11. A piston having an outer shell, a smaller inner shell within said outer shell, and means securing said outer and inner shells together comprising means closing the head of said outer shell, means forming an end wall of said inner shell, and means adjacent the end of said inner shell opposite said end wall securing said inner and outer shells in spaced relationship.

12. A piston having an outer shell, a smaller inner shell within said outer shell, and means securing said inner and outer shells together comprising means closing the head of said outer shell, means forming an end wall of said inner shell, and a thin metallic ribbon arranged with its width vertically disposed and having one of its edge portions united with said head closing means and the other of its edge portions united with said end wall to form a structural head strengthening element.

13. A piston having an outer shell, a head for said outer shell, an inner shell nested within said outer shell and having an end wall located adjacent to but slightly spaced from said head, a corrugated metallic ribbon arranged in the space between said end wall and head, and means securing said ribbon to said end wall and head respectively.

14. A piston having an outer shell, a head for said outer shell, an inner shell nested within said outer shell and having an end wall located adjacent to said head, corrugations in said end wall forming radially extending channels below said head, and means securing said end wall and head together.

15. A piston comprising an outer shell, a head for said outer shell, a central downwardly extending projection upon said head, an inner shell nested within said outer shell, an end wall for said inner shell having a central aperture aligned with said projection, means spacing said end wall from said head to provide channels therebetween, and means securing said parts together.

16. A piston comprising an outer cylindrical stamping, the side walls of said stamping being extruded inwardly of the stamping to form aligned apertures along a diameter of the piston, an inner stamping nested within said outer stamping and secured to said outer stamping by brazing, depending portions on said inner stamping spaced

12

inwardly from said outer stamping and apertured and flanged in alignment with the extruded and flanged portions of said outer stamping, and bearing sleeves positioned in said aligned apertures at each end of said diameter and secured therein as by brazing, said piston being relieved of all initial stresses as a result of said brazing operation.

17. A piston having an outer stamped shell, a smaller inner stamped shell within said outer shell, and means securing said outer and inner shells together comprising means closing the head of said outer shell, means forming an end wall of said inner shell, means spacing said head closing means and said end wall from one another and securing them in spaced relation to form a strengthening element and a plurality of coolant circulating channels therebetween, and means adjacent the end of said inner shell opposite said end wall securing said inner and outer shells in spaced relationship.

18. A piston for an internal combustion engine comprising an outer stamped shell, an inner stamped shell press-fitted within said outer shell, a head on said outer shell, an end wall on said inner shell, means spacing said head and end wall from one another to form coolant channels therebetween, an inlet to said channels at the center of said end wall, and outlets from said channels around the periphery of the piston, said parts being secured together in final position as by brazing, the piston being substantially free of initial stresses as a result of brazing.

19. A piston for an internal combustion engine comprising an outer cylindrical stamping having a lower portion of large diameter and an upper portion of relatively reduced diameter with a top wall extending across the end thereof, an inner stamping nested within said outer cylindrical stamping and having an end wall, a spacer member located between said top and end walls and in contact therewith at spaced points, and means securing said spacer member to said outer and inner stampings to hold said walls so spaced.

FLOYD F. KISHLINE.
